INVENTOR.

UNITED STATES PATENT OFFICE.

ALTON R. MARTIN, OF BUFFALO, NEW YORK.

HEADLIGHT.

1,247,394.

Specification of Letters Patent. Patented July 26, 1920.

Application filed June 20, 1919. Serial No. 825,464.

To all whom it may concern:

Be it known that I, ALTON R. MARTIN, a citizen of the United States, residing at Buffalo, in the county of Erie and State of New York, have invented new and useful Improvements in Headlights, of which the following is a specification.

This invention relates to light projecting means, and more particularly to an automobile headlight.

One of the main objects of this invention is to provide a headlight so constructed as to eliminate the objectionable glare and to direct the light rays downwardly and forwardly of the vehicle.

A further object is to provide a light having a lens associated therewith which is so constructed as to reflect and refract the light rays so as to project the same downwardly and forwardly of the vehicle.

Further objects will appear from the detailed description.

In the drawings:

Figure 1 is a front view of a headlight constructed in accordance with my invention.

Fig. 2 is a central vertical sectional view through the light.

Fig. 3 is a top plan view of the lens.

Fig. 4 is a section taken on line 4--4 of Fig. 3.

In constructing the light, I provide a housing or casing 1 which conforms in shape substantially to one-half of a semi-paraboloid. This casing is normally closed at its forward end by a door 2 which is hinged to the casing by means of sleeves 2^a carried by the door and fitting between sleeves 1^a carried by the casing, the aligned sleeves being connected by pintles 2^b inserted through the same. The casing is further provided with tubular members, not shown, adapted to receive the vertical arms of a fork 3 carried by a standard 4 adapted to be supported by the usual bracket upon an automobile. A lamp bulb 5 is mounted at the rear of casing 1 and above the lower edge thereof, this lamp bulb being connected by a cord 6 to a suitable source of electricity, in the known manner. A horizontally disposed lens 7 is mounted in the bottom of casing 1. The upper surface of this lens is provided with a plurality of substantially V shaped grooves disposed in parallel relation and extending trans-

versely of the lens, these grooves serve to provide a plurality of spaced and integrally connected refracting and reflecting prisms 8, these prisms having their forward faces disposed substantially vertically and their rearward faces at an inclination. The light rays from the bulb or lamp 5 which strike upon the prisms 8 of the lens 7 adjacent the lamp are refracted downwardly through the prisms so as to illuminate the surface immediately in advance of the vehicle. The light rays which strike the prisms more remote from the lamp are reflected upwardly so as to strike the inner reflecting surface of the casing 1 by which they are projected forwardly and downwardly of the vehicle at a decided angle thus insuring illumination of the surface in advance of the vehicle while preventing these light rays from being projected at such a height from the ground surface as to blind the driver of an approaching vehicle. The light rays which strike the outermost series of prisms are directed forwardly and upwardly at an angle to the light rays which are projecting downwardly and forwardly, these two series of light rays intermixing so as to avoid glare or a solid beam of light rays such as would interfere with the vision of the driver in an approaching automobile.

By this construction I insure proper and sufficient illumination for the vehicle carrying the headlight while effectually preventing the objectionable glare incident to the use of headlights of common construction.

Having described my invention, what I claim is:

1. In a headlight, a casing having an inner projecting reflector, a source of light within the casing, and a refracting and reflecting member positioned below the light source and adapted to refract certain of the light rays downwardly onto the traction surface and reflect other light rays against the projecting reflector so as to be projected thereby outwardly of the casing.

2. In a headlight, a casing including a projecting reflector, a source of light within the casing, and a member positioned below the light source and including a plurality of prismatic elements adapted to refract certain of the light rays downwardly onto the traction surface and reflect other light rays against the projecting reflector so as to be projected thereby outwardly of the casing.

to be projected outwardly of the casing thereby.

3. In a headlight, a casing including a projecting reflector, a source of light within the casing, and a closure member for the bottom of the casing positioned below the light source and adapted to refract certain of the light rays downwardly onto the traction surface and to reflect other rays against the projecting reflector so as to be projected thereby outwardly of the casing.

4. In a headlight, a casing of substantially semi-circular vertical cross section, a source of light positioned within said casing, and a plurality of horizontally disposed prismatic refracting and reflecting members mounted in the bottom of the casing in a common plane, said members having their inclined faces directed rearwardly of the

casing and being connected to form a closure for the bottom of the casing.

5. In a headlight, a casing having an inner projecting reflector, a source of light within the casing, and a refracting and reflecting lens mounted within the casing below the source of light and comprising a plurality of parallel integrally connected prismatic elements disposed in a common plane, said prismatic elements being so related to each other and to the source of light as to refract certain of the light rays downwardly onto the traction surface and reflect other rays against the projecting reflector so as to be projected thereby outwardly of the casing.

In testimony whereof I affix my signature.

ALTON R. MARTIN.
